UNITED STATES PATENT OFFICE.

WILLIAM ARTHUR CROWELL, OF DARTMOUTH, NOVA SCOTIA, CANADA.

RAIL-FASTENING.

1,109,046.

Specification of Letters Patent.

Patented Sept. 1, 1914.

Application filed March 23, 1914. Serial No. 826,729.

To all whom it may concern:

Be it known that I, WILLIAM A. CROWELL, of the town of Dartmouth, in the county of Halifax, Province of Nova Scotia, Dominion of Canada, blacksmith, have invented certain new and useful Improvements in Rail-Fastenings, of which the following is the specification.

This invention relates to rail fastenings, and the objects of the invention are to devise a simple and cheap substitute for the spike or the rail-chair now in use, which has the advantages of being not only a positive fastening member and locking device between the rail and the tie, but also a device which may be taken out and replaced many times without impairing its efficiency or damaging the tie.

The invention consists essentially in the novel construction and arrangement of parts hereinafter described, and illustrated in the drawing which forms part of this specification.

In the drawing;—Figure 1 is a side elevation of the fastener, and shows the rail in section. Fig. 2 is an end elevation of the fastener and the "lag screw" used in connection therewith. Fig. 3 is a section taken on the line "A—B" in Fig. 1.

In the drawing, like numerals of reference indicate corresponding parts in each figure.

Referring to the drawing, 10 indicates the fastening member, which has the heel 11 adapted to bear on the surface 12 of the tie 13, and the toe 14 adapted to grip the rail 15 against the tie. The spike 16 is preferably formed integral with the heel and toe, and is offset therefrom at an angle of approximately 60 degrees. This angle may be changed a little one way or the other, but the angular disposition of the spike forms a vital feature of the invention. The toe is raised a little from the heel, in order to permit it to rest on the rail flange 17. The spike 16 commences its angular disposition immediately at the point 18, where the toe commences to hold. The section of the

spike here illustrated is oval (see Fig. 3) having the long side of the oval in line with the grain of the tie, in order not to split the tie.

In securing a rail to the ties with this fastener, the rail is placed in the position it is intended to occupy ultimately, and the fastener is hammered on the place marked 18^a, to drive the spike into the tie. When the fastener is driven home, a "lag screw" or coach screw is inserted in the orifice 19 in the fastener, and driven home partly by hammer then tightened down by wrench, or the like. The spike is offset from the toe part about 60 degrees as previously mentioned, and the coach screw is set in at right angles to the fastener toe and heel, so it will be apparent that the center-lines of the screw and the spike (shown respectively as 20 and 21) are convergent. Should the rail have a tendency to lift, it bears up on the toe, and the heel acts as a fulcrum, so that the fastener cannot become loose by a lifting tendency on the part of the rail. The coach screw is proof against vibration and thus a very perfect lock is obtained.

In removing the fastener, the lag screw is first loosened, and afterward a lever or crowbar is inserted under the heel at the part 22 prepared to receive it. The toe of the fastener is thus made the fulcrum, and the spike is easily loosened, when it may be removed by hand.

The fastener is preferably made of drop-forged iron or of malleable iron in some form, to withstand hammering and rough usage.

What I claim as my invention is:—

1. A rail-fastener comprising in combination a body-piece having a flat tie-engaging flange, a rail-engaging flange offset therefrom, a spike formed integral with said flanges and depending angularly from said tie-engaging flange, said tie-engaging flange having a vertical orifice therethrough at the point of junction of said angular spike, a threaded retaining member having a head and adapted to be passed through

said orifice as regards its shank, and engaging the tie, in a manner to act as a fulcrum for said body-piece.

2. A rail-fastener comprising in combination a body-piece and a threaded tie-engaging member passed therethrough, said body-piece having an obliquely disposed tie-engaging spike offset at the point where the threaded member passes through the body, 10 said body also having a rounded heel adapt-

ed to assist in removal of the device and permit said threaded member to act as a fulcrum.

In witness whereof I have hereunto set my hand in the presence of two witnesses. 15

WILLIAM ARTHUR CROWELL.
